United States Patent Office

Des. 208,462
Patented Sept. 5, 1967

208,462

AUTOMOBILE DOOR PROTECTOR OR THE LIKE
Joseph W. Pearson, 830 Glenwood Road,

Glenview, Ill. 60025

Filed Aug. 25, 1966, Ser. No. 3,593

Term of patent 3½ years

(Cl. D14—6)

The rear of the protector is substantially plain.

I claim:

The ornamental design for an automobile door protector or the like, substantially as shown and described.
